UNITED STATES PATENT OFFICE

SIGMUND KANCLERZ, OF MASPETH, NEW YORK

FOLDABLE CHAIR

Application filed August 23, 1929. Serial No. 387,921.

This invention relates to furniture and in particular to foldable chairs and stools.

An object of the present invention is to provide a chair or stool construction permitting its members to be readily folded from their operative positions into a small and compact package which may be readily carried.

A further object of the invention is to provide chairs or stools of foldable metal members adapted, in one adjusted position, to form a rigid, substantial and comfortable chair or stool and adapted to be folded to carrying position by disengagement of some of the members.

Another object of the invention is to provide a foldable back rest attached to the seat supporting members which may be opened to operative position or folded to a position closely adjacent the members forming the support for the seat and the seat portion itself.

A still further object of the invention is to provide a foldable supporting leg structure enabling the legs, preferably three, to be folded closely adjacent each other or spread out into a self-locking position for supporting the seat portion.

A further object of the invention is to provide a seat portion for a foldable chair or stool which may be partly disassembled and folded compactly about the supporting structure so that the chair or stool can be conveniently carried about.

A still further object is to make the seat portion of several sections movable relative to each other so that in folded condition they may be closely wrapped about the other portions of the chair.

With these and other objects in view my invention includes the construction and operation set forth in the following specification and illustrated in the accompanying drawings.

In the accompanying drawings annexed

hereto and forming a part of this specification, I have shown my invention embodied in foldable chairs or stools having metal frames, but it will be understood that the invention can be otherwise embodied and that the drawings are not to be construed as defining or limiting the scope of the invention, the claims appended to this specification being relied upon for that purpose.

In the drawings—

Fig. 1 is a complete side elevation of a preferred form of the invention shown in open or extended position;

Fig. 2 is a front elevation of the foldable chair shown in Fig. 1;

Fig. 3 is a view of the chair in partially folded or collapsed condition showing the manner of collapsing or folding the members into compact form for carrying;

Fig. 4 is a plan view of the chair shown in Figs. 1, 2 and 3, taken on the plane of line 4—4 of Fig. 1;

Fig. 5 is a detail view in side elevation of disengageable parts of the chair frame;

Fig. 6 is a side elevation of another form of the invention showing a chair or stool without a back and having a flexible fabric seat;

Fig. 7 is a front elevation of the form of the invention shown in Fig. 6;

Fig. 8 is a side view of the form of the invention shown in Figs. 6 and 7, the members thereof having been partially folded to their compact carrying position;

Fig. 9 is an isometric view showing details of construction of the frame members and their relative engagement;

Fig. 10 is a view in elevation of a modified form of supporting leg structure for a chair or stool shown in unfolded or extended position; and

Fig. 11 is a view of the form of supporting leg structure shown in Fig. 10 folded to its compact or carrying position.

In the above-mentioned drawings, I have shown several embodiments or modifications

55

60

65

70

75

90

of the invention which are now deemed preferable, but it is to be understood that other changes and modifications may be made within the scope of the appended claims without departing from the spirit of the invention.

Referring more in detail to the figures of the drawings and first to Figs. 1 to 5, I provide a stool or chair supported by a tripod consisting of a central column or tripod head 10 and three leg members 11. The leg members 11 are pivotally connected adjacent their upper ends to a sleeve 12 which is slidably mounted upon the supporting column 10. Any convenient means may be provided for retaining the sleeve 12 upon the column 10. The legs 11 have portions extending above the sleeve 12 which are adapted to engage in radial slots 13 in the supporting column 10 so that this column 10 may be rigidly supported in vertical position and at a fixed elevation.

The leg members 11 may be held in their outward or extended position by means of radiating arms 14 pivotally attached at their outer ends to the mid-portions of the legs 11 and pivotally attached intermediate their ends to a bracing member 15. The inner ends of the arms 14 coact with the bracing member 15 to brace the leg members 11 when the leg members are extended but do not coact with the member 15 when the legs are folded. The bracing member 15 has a hole of sufficient size to permit the passage of the column 10 therethrough. At the lower ends of the leg members 11, toe plates 16 are adapted to be fastened having a lower surface of considerable area so that the chair may be supported upon pads formed thereby of sufficient area to prevent their sinking into soft ground or cutting into wooden floors.

In the folded position of the chair, the leg members 11 lie closely adjacent the column 10 and the bracing member 15 passes over the column 10, all as shown in Fig. 3.

Upon the upper end of the supporting column 10 is a plate 17 held permanently on the column 10 by a threaded portion and nut or by any other suitable fastening means. This plate 17 has its opposite side portions bent downwardly. Pivoted to the plate 17 are two supporting link frames 18 and 19. The side members of each link frame may be parallel as shown in the drawings and are connected by the tie rod 20 at the end of the link opposite to the plate 17. These side members preferably enter slots at the corners of the horizontal portion of the plate 17 which limit their movement in one direction. The upper ends of the link frames 18 and 19 are connected by two supporting members 21. Upon these members 21 the seat is supported by means presently to be described. The upper end of the front link frame 18 and the front ends of the members 21 are pivotally attached together preferably by the

front tie rod 20. The rear ends of the members 21 have hooks 22 which engage the rear tie rod 20.

The members 21 are each in two sections which are hinged together, the pivots being disposed at 23 as shown in Figs. 1 and 3. The forward portions of the members 21 have a bar 24 connecting their rear ends in rear of the pivots 23. In the extended position of the members 21, the bar 24 engages notches 25 cut in the rear portions of the members 21 and supports the portions firmly in alignment. In folding the chair the members 21 are unhooked from the rear tie rod 20 whereupon the members 21 may be folded upon themselves about the pivots 23. The link frames 18 and 19 may then be pivoted downwardly to positions parallel to and on opposite sides of the central supporting column 10.

The seat 26 is supported rotatably upon the members 21 and is swiveled by means of a swivel joint 31 to a member 28 held between the members 21. As shown, the seat 26 in this embodiment of the invention is formed of a plurality of wooden slats 29 grouped in three sections foldable upon themselves by suitable hinges 30 provided at their opposite ends. In the unfolded or operative position of the chair, the slats 29 extend transversely of the members 21 and are all supported thereon and held in fixed horizontal positions. By swiveling the seat 26 about its swivel joint 31, the seat may be folded. In its fully collapsed position, the seat encloses the link frames 18 and 19 and the supporting leg structure when they are in their folded positions.

It is desired in some forms of the invention to provide a back support or rest as shown in Figs. 1 and 2. This support or rest preferably is so mounted that it also may be readily folded up when the chair is compactly folded. This back support comprises a pair of vertically disposed bars or rods 32 pivotally attached to plates 33 at 34, the plates 33 being secured to the rearwardly and upwardly extending link frame 19. A flat bar 35 connecting the lower extended ends of these back supporting bars 32 is adapted to engage the rear faces or abutments on the plates 33 so that the bars 32 may be supported in their vertical position against further backward movement. These rods 32 may have additional or extension rods 36 extending substantially vertically above them. These extension rods 36 are slotted at their lower ends in a manner to engage a flat bar 37 connecting the upper ends of the first back supporting bars 32 so that the rods 36 may be held in alignment with the rods 32. Below the slots are formed suitable openings so that when these upper supporting rods 36 are raised slightly they may be pivoted about and positioned adjacent the remaining portions

of the chair. These extension members 36 may also have a plate 38 formed between them and secured thereto as by crimping its edges. Enlarged wing members 39 preferably formed of resilient material such as spring wire formed into loops pivotally mounted relative to the rods 36 and plate 38 may be provided. These loops 39 may be folded or unfolded laterally, as clearly shown in Figs. 2 and 3. In the unfolded position, the supporting members 38 and 39 provide a substantial support for the back of the user, rendering the chair comfortable and permitting folding of the back supporting members without materially increasing the size of the chair when in its folded or collapsed condition.

In the embodiment of the invention shown in Figs. 6, 7, 8 and 9, the seat portion comprises a plurality of strips or bands of fabric 40 extending from side to side so that the seat is flexible.

The ends of the fabric strips 40 are first directly attached to clamping strips 42 which are provided with bars 43 extending through them.

them.

The seat is supported by two supporting link frames 41, the side members of which may be parallel as shown in the drawings.

30 These link frames are pivoted at their lower ends to a plate 46 at the upper end of a supporting column or post 47. As this portion of the construction is similar to the form shown in Figs. 1, 2, 3 and 4, further description is thought to be unnecessary. At the upper or free end of each link frame 41 is pivotally mounted an extension link 48, the side members of which may be parallel, and having end members 45 and 49. The side members have hooks 54 at their outer ends. The end member 45 has a projection 44 to which the bar 43 for the clamping strips is attached. These extension links 48 are pivotally attached to the link frames 41 by the members 49 and are adapted to be held in their extended position by movable rods 50 slidably movable in slots in the side members of the links 48. The rods 50 are adapted to engage notches 51 on the outer ends of the side members of the link frames 41 so that the extension links 48 may be supported either in alignment with the link frames 41 or at different angles thereto.

In order to set up the chair or stool in its operative or unfolded arrangement, the link frames 41 are moved to their oblique upwardly extending positions and both of the clamping strip bars 43 are engaged under the hooked portions 54 on the links 48. One of the extension links 48 is made fast by engaging its sliding rod 50 in the notches 51 of one of the link frames 41, and then the other extension link 48 is made tight by engaging a similar sliding rod 50 in the notches 51 in the other link frame 41. To facilitate this

final movement which stretches the bands 40, a handle 52 is pivotally mounted at an intermediate point on the extension link 48; abutments or pins 53 outstanding from the sides of the link 48 serving to restrict the movement of this handle in one direction. With the handle 52 moved to an outer position, a leverage is obtained for forcing the slidable rod 50 into one of its notches 51 so that the bands 40 forming the seat will be tightly stretched. 70 75

The leg structure for supporting the seat shown in Figs. 6, 7, and 8 may be similar to that previously described, but may, if desired, be formed of a slightly different combination of elements as shown in Figs. 6, 7, and 8. The three leg members 56 are pivotally mounted at their upper ends to projections formed on a sleeve 57 slidably mounted on the column 47. A radial bracing member 58 is provided attached to the lower end of the column and having slots through which the legs 56 extend. Intermediate portions of the leg members 56 have notches which engage with the bracing member when the legs are extended outwardly.

The leg members 60 in the modified form of leg structure shown in Figs. 10 and 11 are pivotally attached to integral projections on the upper end of a sleeve 61. The sleeve 61 is slidable upon a central supporting column 66 such as 10 or 47. Surrounding the sleeve 61 and slidable thereon is a bracing member 62 having projections for pivotally attaching the radial supporting arms 63 near their inner ends. The inner ends of these arms 63 enter elongated slots 65 formed in the sleeve 61 and coact with the bracing member 62 to brace the leg members 60 when the leg members are in their extended position. To close the leg members to carrying position, it is only necessary to move the ring 62 upward on the sleeve 61. 95 100 105

I claim:

1. In a foldable chair, the combination of a foldable seat, a tripod comprising a tripod head and three legs, two link frames pivoted to said tripod head and supporting said seat, a back formed in parts so as to be foldable on itself and pivoted to one of said link frames, means for holding said seat extended, means for holding said tripod legs extended, means for holding said link frames extended, and means for holding said back extended, all of said mentioned means being releasable to permit said parts to be folded about said tripod head. 110

2. In a foldable chair, the combination of a foldable seat, a tripod comprising a tripod head and three legs, two link frames pivoted to said tripod head and supporting said seat, the side members of each one of said link frames being parallel, a back formed in parts so as to be foldable on itself and pivoted to one of said link frames, means for 120 125 130

holding said seat extended, means for holding said tripod legs extended, means for holding said link frames extended, and means for holding said back extended, all of said mentioned means being releasable to permit said parts to be folded about said tripod head.

3. In a device of the character indicated, a central column, supporting means therefor, 10 two link frames each pivoted at one end to said central column, the other ends of said link frames being detachably connected by supporting members, said supporting members being hinged intermediate their ends 15 and foldable upon themselves, a seat made up of a plurality of sections and supported by said supporting members, said sections being hinged together and foldable upon themselves, said seat being connected to said 20 supporting members and being rotatable relative thereto; said supporting means for said central column, said link frames, said supporting members, and said seat being foldable upon said central column.

25 4. In a device of the character indicated, a central column, supporting means therefor, two link frames each pivoted at one end to said central column, extension links each pivoted at one end to said first mentioned 30 link frames, a seat attached to said extension links, and means for holding said extension links at adjustable angles to said first mentioned link frames; said supporting means for said central column, said link frames, 35 said extension links, and said seat being foldable upon said central column.

50 5. In a device of the character indicated, a central column, a seat supported thereby, a sleeve slidably mounted on said column, 40 a plurality of leg members pivoted to said sleeve and forming a support for said column, said leg members being foldable upon said central column, a bracing member having a hole therein, and a plurality of arms, each of said arms being pivotally attached at one end to one of said leg members and being pivotally attached intermediate its ends to said bracing member, the other end of each of said arms coacting with said 45 bracing member to brace said leg members when said leg members are extended but not coacting with said bracing member when said leg members are folded upon said column, said column being encircled by said 55 bracing member when said leg members are folded upon said column.

60 6. In a device of the character indicated, a central column having radial slots therein, a seat supported by said central column, a sleeve slidably mounted on said central column, a plurality of leg members pivoted intermediate their ends to said sleeve and having portions adapted to engage in said slots so as to form a support for said column, 65 said leg members being foldable upon said 70

central column, a bracing member having a hole therein, and a plurality of arms, each of said arms being pivotally attached at one end to one of said leg members and being pivotally attached intermediate its ends to said bracing member so as to coact with said bracing member to brace said leg members when said leg members are extended, said central column passing through the hole in said bracing member when said leg members are folded upon said central column.
